[57] CLAIM

The ornamental design for a rolling gamepiece, as shown and described.

DESCRIPTION

FIG. 1 is a perspective view of the rolling gamepiece, showing my new design;

FIG. 2 is a left side view thereof, with the right side view being substantially identical of the gamepiece position shown in FIG. 1;

FIG. 3 is an end view thereof but rotated from the position of FIGS. 1 and 2;

FIG. 4 is a top view thereof as seen in the position of FIG. 3; and,

FIG. 5 is a bottom view thereof as seen in the position of FIG. 3.
